UNITED STATES PATENT OFFICE.

JAMES W. MURRY, OF BROOKLYN, NEW YORK.

VOLTAGE STABILIZER.

Application filed April 15, 1924. Serial No. 706,719.

My invention relates to electrical installations, and particularly to those in which a direct current is caused to flow in a given circuit. It consists in means for eliminating from the voltage under which such a current flows, fluctuations, such as may exist and commonly do exist in the d-c voltage generated by ordinary means, flows.

My invention is applicable generally, wherever there is need for a direct current flowing under substantially constant voltage, and under voltage more nearly constant than is otherwise the case with a direct current generated in usual manner. I have found practical application for my invention in correcting and stabilizing the voltage under which the current employed to energize the receiving apparatus of a wireless telephony system, flows, and in that particular application I shall describe it. But the fact will be plain that the radio receiver or sender is a mere instance of an opportunity for advantageous use of the invention, and that the invention in its broader and more general aspect is by no means limited to this particular application.

The accompanying diagrams will serve to illustrate the application of the invention to the wireless service indicated above and the practical consequence and effect of such application. Fig. I shows the component electrical units and their connections, when my invention is employed in application to a radio receiver of typical form or type. Fig. II is a chart on a system of co-ordinates illustrating voltage variation and illustrating the effect of the presence of my invention, to negative and eliminate voltage variation. Fig. III is a vector diagram, illustrating in another way the same matter. Fig. IV is a diagram similar to Fig. I and illustrates a modification in the application of the invention. Figs. V, VI, and VII illustrate other modifications.

In a radio receiver or sender employing an electron tube both the plate circuit and filament circuit require for successful service a current flowing under a substantially constant voltage to energize the receiver. Commonly a battery is employed to afford such a current, but it is very desirable to be able to dispense with a battery and to energize the receiver with current derived from the familiar domestic supply. The difficulty, insurmountable hitherto, preventing the use of the familiar domestic supply

for this purpose is that, whether supplied as direct current or supplied as alternating current and rectified, voltage variations are of such dimensions as to render its use unsatisfactory and impractical.

Fig. I shows a line of flow from A through a resistance unit B, to C, and through this line a direct current may, it will be understood, be caused to flow. A shunt line leads from an adjustable tap D in the resistance unit B, through a detector tube E to the main line again at F. As thus far described, the flow of current through the shunt line D—E—F is obviously subject to whatever variations in voltage there may be under which the current is supplied. This condition is indicated in Fig. II, where a waved line G—H indicates a voltage varying from time to time through a range of twenty volts, from a potential of 90 volts to 110. The variation is here shown to be recurrent and regular in periodicity and in value, but it will appear as I proceed that my invention is not conditioned by such circumstances, but is applicable to correct any variation, regular or otherwise.

Returning to Fig. I, my invention is found in the provision of two transformers I and J, of which the primaries are included in shunt lines between the points A and C, and the secondaries are included in the line of flow already specified, from A to the resistance unit B and thence through the shunt line D—E—F. The secondary coils are, in relation to the normal line of flow A—B—D—E—F, oppositely arranged, to the end that the voltages induced in these two coils (whatever their particular values may be) shall be induced with opposite effect upon the current otherwise normally flowing in the line A—B—D—E—F. That is to say, in one transformer the induced voltage is added to the normal voltage and in the other it is subtracted from the normal voltage. This condition of oppositely acting induced voltages is indicated by the two dotted arrows set opposite the two transformers I and J in Fig. I.

I so particularly proportion the resistance and reactance of the primary windings of the two transformers I and J that the transformer I, which induces voltage in opposite direction to the normal voltage of the line of flow, shall induce a voltage greater than the voltage variation of normal flow, and the transformer J, which induces voltage

in like direction with the normal voltage of the line, shall induce a voltage less than the voltage variation of normal flow.

It will be understood that, so long as the voltage under which the direct current flows normally in the line A—B—D—E—F, remains constant, the transformers I and J will remain quiescent. When the voltage under which the normal current flows changes, the two transformers will become active. Suppose the change to be by way of increase, the increment being say 20 volts,—from 90 volts to 110. One of the transformers, the transformer J, will tend 15 to augment the variation, making it greater; that is to say, transformer J tends to increase the voltage to a value greater than 110 volts. The other transformer, the transformer I, sets up a countervailing voltage, 20 greater than the accession. The accession in value is 20 volts. The effect of transformers I and J then is to impose on the line an alternating voltage of 20 volts. But this imposed voltage is opposite in 25 direction to the variations in the applied voltage, and the consequence and effect is to reduce what otherwise would be a varying voltage with a maximum value of 110 volts, and to afford a resulting unvarying voltage 30 of 100 volts, the desired result. Deficiencies in voltage will similarly be rectified and always, transformers I and J being present, the effective voltage through the shunt line D—E—F will be constant, 35 and that is the desired result.

Referring again to the chart, Fig. II, the waved line G—H represents the voltage of the line as, but for my invention, it might rise and fall. The consequence and effect 40 of the presence of the transformers I and J is to set up a countervailing variation of voltage, indicated by the dotted and oppositely waved line X—Y. This dotted line indicates the aggregate, the sum of the voltages set up by the transformers. This 45 countervailing voltage will cancel the voltage variations otherwise existing. The result will be that the voltage will at all times remain normal, as indicated by the straight line G—H.

Turning to Fig. III, the diagram to the left indicates the effect of transformer I alone. Here the arrow K—L indicates an alternating voltage equal to the difference 50 between the applied voltage and the steady average voltage. On Fig. II it is the difference between "applied voltage" and the straight line G—H representing the steady average voltage. K—M and K—N are the component variations in the voltage, K—M is the inductance drop, K—N is the resistance drop, and K—O, opposite in direction 55 to K—M and greater than K—M, represents the voltage induced in the secondary. The next diagram similarly illustrates the ef-

fect of transformer J alone. K—L is as before the variation in the applied voltage which makes the transformer active. K—P and K—Q are the components of this voltage, K—P in the inductance drop, K—Q 70 in the resistance drop, and K—R indicates in value and direction the voltage induced in the secondary. The third diagram, the diagram to the right, shows the combined effect of transformers I and J. The resultant of forces K—O and K—R is K—S, and K—S is equal in value and opposite in direction to K—L, the initial disturbance. Thus voltage disturbance is reduced to zero and eliminated. 80

It will of course be understood that the component units of the transformers, primary and secondary, and the resistances T, U, are adjustable, within the knowledge and skill of the art, to accomplish with practical precision that which is theoretically plotted and illustrated in the charts. Thus I indicate in Fig. I adjustment in the secondary of transformer J and also in the resistance U of the same transformer. 85 Given these two adjustment devices, the apparatus can be suited to existing conditions, whatever they may be. 90

I have, as a practical illustration, shown countervailing, oppositely acting transformers, whose effective transformation ratios are $1:1\frac{1}{2}$ and $1:\frac{1}{2}$. It will be understood that the essential thing is to achieve a difference (oppositely acting) between the induced voltages, equal (approximately) to the variations in the applied voltage. Any particular values for these transformation ratios, such as to maintain that difference, will, manifestly, achieve, and be within the contemplation of, my invention. 100

It is not in all cases requisite to make correction and to eliminate voltage with such nicety and with such completeness as is achieved by the apparatus illustrated in Fig. I. In a sender or in a receiver of a radio installation, when the incoming radio waves are strong, or when a loud speaker is to be operated, such nicety of result may exceed the necessity. In such case the arrangement shown in Fig. IV will be found adequate. 110

In this case a single transformer I' is employed, adjusted to bring a variable induced voltage to bear, whose value at any given moment is substantially equal to the departure from normal which at that moment is found in the voltage under which the current flows in the primary and opposite in direction. That is to say the transformation ratio in Fig. IV is 1:1. This is a simple arrangement, but incapable of completely smoothing out variation in voltage of the supplied current. The reason, why this arrangement is incapable of completely eliminating voltage variations, is because the 120 125 130

counter electro-motive force of the transformer is not exactly 180° out of phase with the electro-motive force in the primary. That is to say, and with reference to the 5 first diagram of Fig. III, the voltage of the primary is exerted in the direction indicated by the arrow K—L; the voltage of the secondary lies in the direction indicated by the arrow K—O (though the value is not K—O; 10 the value is equal to K—L). But K—L and K—O are not exactly opposite in direction. There is a small failure of complete balance. But, as I have said, the margin is slight and for many applications inconsequential. So 15 that practically and for many purposes I may in the practice of my invention use a single transformer, as illustrated in Fig. IV, although for precision the more perfect balance realized in the use of two transformers, as illustrated in Fig. I, is desirable. 20

While I have shown the use of two separate transformers in the description of this device, it will be understood that similar results can be obtained by combining the two 25 in such a way that the two primaries are as before, and a single secondary winding embraces the magnetic circuits of both transformers. This is diagrammatically illustrated in Fig. V. Here two primaries, I 30 and J, have their secondary in common, and this secondary is in the line of flow from A to the apparatus to be energized, in this case a radio receiver.

The transformer may be an auto-transformer. In Fig. VI I show two transformers 35 (in that respect adopting the arrangement of Fig. I) but one of the transformers, the transformer I^2 , is here indicated to be an auto-transformer, having its primary and 40 secondary windings connected in series.

Fig. VII shows the arrangement of Fig. IV, but here again the transformer I' of Fig. IV is replaced by the auto-transformer I^2 .

I claim as my invention.

1. A voltage stabilizer for direct-current flow including, in combination, in a circuit of three branches each of which is arranged in shunt relatively to the others, two transformers, the primaries of the transformers being arranged one in each of two of the 50 three branches, and the secondaries of the transformers being arranged in series and oppositely with relation one to the other in the third of the three said branches.

2. A voltage stabilizer for direct-current flow including, in combination, in a circuit of three branches each of which is arranged in shunt relatively to the others, two transformers, the primaries of the transformers being arranged one in each of two of the 55 three branches, and the secondaries of the transformers being arranged in series in the third of the three said branches and oppositely with respect one to the other, one of said transformers being of adjustable 60 value.

3. A method of stabilizing the voltage of a direct current flowing in a conductor which consists in imposing upon the current as it flows two increments of induced voltage induced by variation in the voltage of the current to be stabilized, the two increments being opposite in direction and when aggregated with the variation in the voltage of the current to be stabilized effecting cancellation thereof. 70

In testimony whereof I have hereunto set my hand.

JAMES W. MURRY.
